F. W. COFFING

FREE CHAIN HOIST

Filed Sept. 12, 1922

Patented Aug. 7, 1923.

1,464,259

UNITED STATES PATENT OFFICE.

FREDRICK W. COFFING, OF PERRYSVILLE, INDIANA.

FREE-CHAIN HOIST.

Application filed September 12, 1922. Serial No. 587,846.

To all whom it may concern:

Be it known that I, FREDRICK W. COFFING, a citizen of the United States, and a resident of Perrysville, in the county of Vermilion and State of Indiana, have invented certain new and useful Improvements in Free-Chain Hoists, of which the following is a specification.

This invention relates to an improvement in chain hoists, and the object of the invention is to provide a chain hoist wherein the chain operates or extends through a frame so as to be housed and protected, guided to partake of its proper movements and constrained to operate in its proper field or sphere of action whereby a substantial length of chain may be utilized without portions of the chain being in the way or being in danger of becoming entangled with itself or surrounding objects or structures.

Another object is to provide a chain hoist of this character in which the chain and frame are so organized with each other and with the driving mechanism that the heavy stresses imposed upon these parts are evenly and properly distributed thereby endowing the hoist with features of strength and durability and ease of operation not approached by devices heretofore proposed.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a view in side elevation, illustrating the preferred embodiment of the invention;

Figure 2 is a view thereof in front elevation;

Figure 3 is a detail view in section, showing the frame construction on line 3-3 of Figure 2;

Figure 4 is a similar view showing the frame construction on line 4-4 of Figure 1; and

Figure 5 is a sectional view on line 5-5 of Figure 1.

Referring to the drawings wherein for the sake of illustration is shown the preferred embodiment of the invention, the numeral 10 designates an elongated channel frame, preferably constructed of steel or

cast iron and embodying a back wall 11, side walls 12 and 13 and longitudinal flanges 14 and 15 integrally formed with the side walls 12 and 13 of the frame and extending the full length of the frame, so as to partially, although not entirely, close the open side of the channel. This channel frame provides a channel-way 16 of such size and contour that the hoist chain, designated at 17, has a smooth sliding fit therein, the hoist chain being extended through the channel way 16, as shown in the drawings. This hoist chain 17 is of course made up of a series of links pivotally connected with each other and may be and preferably is of substantial length. The upper ends of the side walls 12 and 13 of the channel frame are inclined as indicated at 18 in Figure 1, and the side flanges integrally formed with these side walls are curved rearwardly, as indicated at 19 in Figure 1 so that as the chain leaves the upper end of the channel way 16 it is deflected rearwardly and thus automatically disposed so as to hang down along the closed back wall 11 of the channel frame, the hanging portion of the chain 17 being thus disposed out of the way and in a position where it cannot become entangled with the remainder of the chain or with surrounding structures or objects.

At the lower end of the channel frame 10 the side walls 12 and 13 are enlarged or extended laterally to provide spaced wings or bearing plates 20 and 21 (see Figure 4). As shown in the drawings, these bearing plates 20 and 21 are of relatively heavy construction so that the flanges 14 and 15 are merged or blended into them.

Driving mechanism is provided for the chain 17 and preferably includes a short drive shaft or axle 22 journaled in bearings provided therefor in the bearing plates 20 and 21 and having a squared extension 23 with which a crank or lever having a ratchet device is adapted to coact. Of course it is to be understood that means other than the crank and lever equipped with the ratchet device may be employed, if desired, for imparting motion to the drive shaft or axle 22. A drive sprocket 24 is keyed or otherwise fixed to the drive axle 22 and is arranged to operate in between the plates 20 and 21, the drive sprocket having teeth 25 which extend into spaces between the links of the chain 17 and coact with these links to impart the desired lift or other motion to the

- chain 17. A safety dog 26 is pivotally mounted on the side plates 20 and 21, as indicated at 27, and is engageable with the teeth 25 of the drive sprocket to prevent retrograde movement thereof. The dog 26 includes a relatively long and heavy handle portion 28 which serves to automatically throw the dog into engagement with the teeth of the sprocket 24 and which also affords a ready means for moving the dog out of engagement with the sprocket when such is desired.
- The lower end of the chain preferably has a swiveled connection 30 with a hook 31.
- 15 A strap 32 embraces the side walls 12 and 13 at the upper end of the frame 10 and is bolted, as at 33, to these side walls. A hook 34 is provided and has swiveled connection, as at 35, with the upper end of the strap 32.
- 20 It is to be understood of course that the hook 34 affords a convenient means for suspending the hoist from any permanent structure or support whereas the hook 31 facilitates the connection of the chain of the hoist 25 to the object to be lifted.
- With this organization, the chain operating in the channel ways 16 is at all times positively engaged with the drive sprocket 25 and thus irrespective of the load the drive 30 sprocket is capable of controlling and imparting the proper movements to the chain. Moreover a substantial length of chain may be utilized since with the arrangement shown the chain may not become entangled 35 with surrounding objects or with itself. Again the arrangement shown is capable of receiving a powerful and efficient drive since the projecting portion 23 of the drive shaft or axle is adapted to cooperate with either 40 the crank, a lever equipped with the ratchet device or a motor drive or the like and irrespective of what means is utilized to rotate the drive shaft or axle 22 the force is 45 efficiently applied to lift the object suspended from the lower end of the chain.
- 45 I claim:
1. A chain hoist having an elongated channel frame including a back wall and side walls provided with longitudinally extending flanges partially closing the open side of the channel, a chain extending through the channel of said frame, said side walls of said channel having extensions at the lower end thereof constituting bearing 50 plates, the bearing plates extending laterally from the open side of the channel frame and including a sprocket having teeth engaged with the chain.
2. A chain hoist having an elongated channel frame including a back wall and side walls provided with longitudinally extending flanges partially closing the open side of the channel, a chain extending through the channel of said frame, said side 55 walls of said channel having extensions at the lower end thereof constituting bearing plates, the bearing plates extending laterally from the open side of the channel frame, driving mechanism including a drive axle rotatably mounted on the bearing plates and having a shank projecting therefrom and adapted to coact with actuating means, a drive sprocket fixed to the shaft and arranged in between the bearing plates, said 60 drive sprocket having teeth extending toward the back wall of the channel frame and engaged with the chain.
3. A chain hoist having an elongated channel frame including a back wall and side walls provided with longitudinally extending flanges partially closing the open side of the channel, a chain extending through the channel of said frame, said side 65 walls of said channel having extensions at the lower end thereof constituting bearing plates, the bearing plates extending laterally from the open side of the channel frame, driving mechanism including a drive axle rotatably mounted on the bearing plates and having a shank projecting therefrom and adapted to coact with actuating means, a drive sprocket fixed to the shaft and arranged in between the bearing plates, said 70 drive sprocket having teeth extending toward the back wall of the channel frame and engaged with the chain.
3. A chain hoist having an elongated channel frame including a back wall and side walls provided with longitudinally extending flanges partially closing the open side of the channel, a chain extending through the channel of said frame, said side 75 walls of said channel having extensions at the lower end thereof constituting bearing plates, the bearing plates extending laterally from the open side of the channel frame, driving mechanism including a drive axle rotatably mounted on the bearing plates and having a shank projecting therefrom and adapted to coact with actuating means, a drive sprocket fixed to the shaft and arranged in between the bearing plates, said 80 drive sprocket having teeth extending toward the back wall of the channel frame and engaged with the chain.
4. A chain hoist having an elongated channel frame including a back wall and side walls provided with longitudinally extending flanges partially closing the open side of the channel, the channel thus defined providing a guideway, a chain extending through the guideway, driving mechanism carried by the channel and cooperable with the frame through the open side of the channel, said guideway having at its upper end means for deflecting the chain to hang down 85 along the closed side of the channel.

FREDRICK W. COFFING.
